UNITED STATES PATENT OFFICE.

JOHN R. HIRSH, OF SYRACUSE, NEW YORK.

DESIGN FOR A HAT-HOOK SHELL.

SPECIFICATION forming part of Design No. 29,565, dated November 1, 1898.

Application filed October 10, 1898. Serial No. 693,186. Term of patent 7 years.

To all whom it may concern:

Be it known that I, JOHN R. HIRSH, a citizen of the United States, residing at Syracuse, county of Onondaga, and State of New York, 5 have invented and produced a new and original Design for Hat-Hook Shells, of which the following is a specification, reference being had to the accompanying drawings, forming part thereof.

Figure 1 is a top plan view thereof. Fig. 2 is a side view thereof, showing the inclosed spring partly in dotted lines. Fig. 3 is a view of the lower end.

As shown in the drawings, the leading or 5 material feature of my design consists in a shell *a*, substantially rectangular from a top plan view and provided with lateral ears *b*, perforated, by which it is secured in substantially the position shown in Fig. 1.

The sides *c* of the shell are cut away or provided with a recess *d*, as shown in Fig. 2, *e* being the ends of the shell.

f is a strap-spring constructed substantially as shown, mounted within the shell and having its free end bent, as shown at *g*, so as to 25 frictionally engage the rim of the hat between it and the base, to which the shell is secured in an upright position.

What I claim is—

The design for a hat-hook shell, substantially as herein described and shown.

In witness whereof I have hereunto set my hand this 7th day of October, 1898.

JOHN R. HIRSH.

Witnesses:

HOWARD P. DENISON,
M. A. FRANKLIN.
